SINE WAVE TEMPLATE

Nadeem F. Audeh, 12048 Downey Ave., Downey, Calif.

Filed May 24, 1963, Ser. No. 75,044

Term of patent 14 years

(Cl. D52—6)

FIG. 1.

FIG. 2.

FIG. 3.

FIGURE 1 is a top plan view of a sine wave template showing my new design;

FIGURE 2 is a side elevational view thereof; and

FIGURE 3 is a longitudinal cross-sectional view, being taken substantially on the horizontal plane of line 3—3 of FIGURE 1, looking in the direction of the arrows.

I claim:

The ornamental design for a sine wave template, as shown.
